(57) **CLAIM**

The ornamental design of a cat litter pan, as shown and described.

DESCRIPTION

FIG. 1 is a front perspective view of the cat litter pan of the present design.

FIG. 2 is a front elevation view of the cat litter pan of FIG. 1. FIG. 3 is a rear elevation view of the cat litter pan of FIG. 1. FIG. 4 is a left side elevation view of the cat litter pan of FIG. 1.

FIG. 5 is a right side elevation view of the cat litter pan of FIG. 1.

FIG. 6 is a top plan view of the cat litter pan of FIG. 1; and, FIG. 7 is a bottom plan view of the cat litter pan of FIG. 1. The broken lines showing the structural reinforcement ribs on the bottom surface of the cat litter pan form no part of the claimed design.
